(57) **CLAIM**

The ornamental design for an automotive dress air freshener for attachment to rear view mirror, as shown and described.

DESCRIPTION

FIG. 1 is a front top perspective view of an automobile dress air freshener for attachment to a rear view mirror showing my new design; and,

FIG. 2 is a rear perspective view thereof.

The broken line showing of environmental structure in FIGS. 1 and 2 is for illustrative purposes only and forms no part of the claimed design.
